Application filed January 9, 1899. Serial No. 701,678. Term of patent 3½ years.

To all whom it may concern:

Be it known that I, GODFREY H. HARRIS, a citizen of the United States, residing in the city, county, and State of New York, have invented and produced a new and original Design for Game-Counters, of which the following is a specification, reference being had to the accompanying drawings, forming part thereof.

As shown in the drawings, the leading or material feature of my design consists in a circle inclosing two golf-clubs crossing each other, a golf-flag, and two golf-balls.

Having described my invention, what I claim as new, and desire to secure by Letters Patent, is—
